ATTORNEY

UNITED STATES PATENT OFFICE

146,138

DESIGN FOR A PEN RACK OR SIMILAR ARTICLE

Wallace Harwood, New York, N. Y., assignor to Academy Award Products, Inc., a corporation of
New York

Application April 11, 1946, Serial No. 128,474

Term of patent 7 years

(CL. D74—13)

To all whom it may concern:

Be it known that I, Wallace Harwood, a citizen of the United States, residing at New York, in the county and State of New York, have invented a new, original, and ornamental Design for a Pen Rack or Similar Article, of which the following is a specification, reference being had to the accompanying drawing, forming part thereof.

I claim:

The ornamental design for a pen rack or similar article, as shown.

WALLACE HARWOOD.
